LIQUID AND POWDER DISPENSING
CONTAINER

Kenneth D. Meredith, Toledo, Ohio

Application March 27, 1936, Serial No. 71,220

2 Claims. (Cl. 221—65)

This invention relates to new and useful improvements in containers especially adapted for tooth powder but which can be employed for various other granulated and pulverized substances and liquids.

The principal object of the present invention is to provide a powder dispensing can wherein the powder is dispensed to a position on the can for use in predetermined quantities.

Another important object of the invention is to provide a dispensing can for powder and like substances which will dispense its contents in predetermined amounts to the end that only that amount required for immediate use will be dispensed.

These and various other important objects and advantages of the invention will become apparent to the reader of the following specification.

In the drawing:

Figure 1 represents a side elevational view of the container.

Figure 2 is a fragmentary side elevational view of the container with the closure moved to a position exposing the basin.

Figure 3 is a top plan view of the structure shown in Figure 2.

Figure 4 is a vertical fragmentary sectional view through the structure shown in Figure 1.

Figure 5 represents a cross sectional view taken substantially on the line 5—5 of Figure 2.

Figure 6 is a fragmentary vertical sectional view of a modified form of the invention showing the hinged top in broken lines in open position.

Figure 7 is a top plan view of another form of the invention.

Referring to the drawing wherein like numerals designate like parts, it can be seen that numeral 5 represents the receptacle of the formation commonly used for containing tooth powder and like substances. The receptacle 5 is provided with the bottom 6 and an outwardly disposed rib 7 adjacent its upper end against which the depending apron portion 8 of the top 9 can abut, the apron 8 snugly engaging the upper portion of the can as shown in Figure 4.

Numeral 10 represents the cover or closure which is manually movable and this cover 10 is provided in its bottom with a recess receiving the upper portion of the dispensing tube 12. As a matter of fact this end portion of the tube 12 is secured in the recess 11 to the cover 10 and its depending portion extends downwardly through the circular opening 13 in one end of

the top 9 and is flared outwardly at its lower end as at 14 to prevent displacement of the cover 10 from the top 9. Thus the cover 10 is swivelly connected to the top 9. This dispensing tube 12 is provided with a short circumferentially extending slot 15 which communicates the interior of the tube 12 with the shallow egg shaped basin 16 in the top surface of the top 9. It can be seen, that by inverting the container 5 as shown in Figure 4, some of the powder in the 10 container will pass through the tube 12 and slot 15 and fill up the basin 16.

The receptacle can now be righted and the cover 10 swung to the position shown in Figure 3 to expose the filled basin 16. The powder in the 15 basin 16 can now be used as desired. In this position by-pass between basin and receptacle is closed.

A modification is shown in Figure 6 wherein the receptacle is denoted by reference character 20 5a. The top 9a is provided with an egg shaped basin or depression 16a in the top side thereof which communicates with the opening 12a through the top 9a by way of a much shallower by-pass 15a. The opening 12a is formed by 25 tapering cuts in the bottom of the top 9a and terminates and opens at its deeper end with one end of the by-pass 15a. Thus it can be seen that with the hinged top 10a disposed over the top 9a, powder can be shaken into the basin 16a 30 and subsequently the cover 10a can be swung to the dotted line position shown in Figure 6 so that the powder in the basin 16a can be used.

Another form of the invention is shown in Figure 7 wherein the top is denoted by reference 35 character 9' and the basin by reference character 16'. Instead of the opening 12a, an opening 12' is formed entirely through the top 9' in a vertical direction and this opening 12' communicates with the basin 16' by a shallow by- 40 pass or cross over 15'. The movable closure 10' is pivotally connected as at 10b to the top 9'.

While the foregoing specification sets forth the invention in specific terms, it is to be understood that numerous changes in the shape, size and 45 materials may be resorted to without departing from the spirit and scope of the invention as claimed hereinafter.

Having described the invention, what is claimed as new is:

1. A receptacle of the character described comprising a container provided with a top having a shallow basin therein, a swingable closure connected to the said top, a by-pass between the basin and the interior of the container, said by- 55

pass consisting of a tube depending from the closure and swivelly connected to the said top, said tube having its interior communicating with the interior of the container and provided with 5 a slot in the side thereof communicating the interior of the tube with the basin.

2. A receptacle of the character described comprising a container provided with a top having a shallow basin therein, a swingable closure connected to the said top, a by-pass between the 10

basin and the interior of the container, said by-pass consisting of a tube depending from the closure and swivelly connected to the said top, said tube having its interior communicating with the interior of the container and provided with 5 a slot in the side thereof communicating the interior of the tube with the basin, said closure being adapted to snugly hug the top surface of the said top.
